UNITED STATES PATENT OFFICE.

GEORGE BENDER, OF NEW YORK, N. Y., ASSIGNOR TO B. & T. COIL FORMER & TOOL CO.
INC., OF NEW YORK, N. Y.

ARMATURE-COIL WINDING AND SHAPING DEVICE.

Application filed December 8, 1923. Serial No. 679,417.

This invention relates to a device for producing improved armature coils and particularly to improvements on the device covered by Patent No. 1,460,737, issued July 3rd, 5 1923, to George W. Townsend, with whom I am associated.

Armature coil devices for producing coils for dynamo-electric machines are known, and particularly types producing form-10 wound armature coils. The present invention deals, however, with a device by which not only the coil may be wound, but also shaped which also permits the spreading or forming of the coil without necessitating the 15 wound coil to be entirely released from the machine and placed in a different device for spreading the coil.

A very important feature covered by the 20 aforementioned patent is the method and means whereby the end loops or noses of the wound coil are released from their winding posts and clamped, preparatory to spreading or forming in such a manner, that the wire between the noses is bent at a clamping line 25 which coincides with the tangent passing through the outermost point of the inner periphery of the smallest wire of the noses, which point lies in the longitudinal center line of the originally wound plane coil when 30 it is released from the winding posts.

The advantages derived from this manner 35 of producing the coils are, firstly, the elimination of long noses which are impractical in producing compact armatures; secondly, 40 the saving of space and wire and thirdly, the production of exactly like shapes of uniform dimensions when once the device is set to produce a certain form of a coil.

The objects of the present invention are 45 to enhance the practicability and improve the operation and increase the adaptability of such a device, while at the same time, a greater speed is achieved in production of the desired coils.

Another object of my invention is to provide 50 in such device, improved wire receiving or gauging means which are made adjustable and permit a greater variance of settings to accommodate different sizes of wire for coils of various dimensions.

Another object of my invention is to pro-

vide improved clamping means for the wound coils, whereby a quick adjustment and a ready removal of the spread coil is possible.

55

Another object of my invention is to provide improved holders, guides or supports for the clamps, which latter are to follow uniformly the spreading operation of the coil, said improved holders permitting an 60 automatic adjustment of said clamps in all directions.

Another object of my invention is to provide in my device, an adjustable guide bar adapted to change its angular relation to 65 the main or guide frame of my device, so that the spread operation may take place at various angles whereby special shapes of coils may be produced.

Another object of my invention is to provide in connection with such machine, an operating mechanism, whereby the rapid spreading by either hand or power may be accomplished.

Another object of my invention is to provide in connection with such mechanism, an automatic stop device which is adjustable so that a coil may be spread to a desired degree, and which device will automatically 70 arrest the further spreading of the coil.

75

Another object of my invention is to provide various manual means for spreading a coil and means for actuating the spreading mechanism.

Another object of my invention is to provide means whereby the spreading mechanism may be actuated by power when so desired.

85

The foregoing and further objects will be more fully apparent from the following description and the accompanying drawings, forming part of this specification, but illustrating only a few of the possible forms of my device, intended for the various purposes. Therefore, it is obvious that in working out this invention in practice, changes may be made in the construction, without departing from the broad scope of my idea of the principle, for which they are intended.

95

Referring to the drawings,

Figure 1 is a plan view of my device.

Figure 2 and Figure 3 are adjustable

100

block members adapted to be associated with the wire receiving carriages.

Figure 4 is an enlarged side elevation, partially in section of a portion of a carriage with clamping means for said blocks.

Figure 5 is a modified form of clamping means for such blocks.

Figure 6 is an enlarged detail view, partially in section of the adjustable end of the 10 coil nose clamping means of my device.

Figure 7 is a modified form of the coil nose clamping means of my device.

Figure 8 is another modified form of the coil nose clamping means of my device.

Figure 9 is a partial detail view of one 15 form of my adjustable guide bar, including part of the coil spreading mechanism.

Figure 10 is a modified form of an adjustable guide bar, also with a part of the coil 20 spreading mechanism.

Figure 11 is a cross-sectional view through the guide bar taken on line 11—11 of Figure 9.

Figure 12 is a top view of part of the 25 clamp support of my device.

Figure 13 is an elevation thereof with the bolt left out.

Figure 14 is a partial front elevation of the other part of the clamp support.

Figure 15 is a side elevation, partially in 30 section, thereof.

Figure 16 shows a side elevation partially in section of a modified form of my device.

Figure 17 is a detail view, partially in 35 section therethrough, which is taken on line 17—17 of Figure 18.

Figure 18 is a detail view in section, taken on line 18—18 of Figure 17.

Figure 19 is a sectional detail view taken 40 on line 19—19 of Figure 17.

Figure 20 is a partial detail view and partial in section of the upper or movable carriage of my device.

Figures 21, 22 and 23 represent modified 45 forms of the adjustable guide bar and of the carriage operating mechanism.

Figure 24 is another modified form of the guide bar and carriage operating mechanism.

Figure 25 is a partial detail view of the 50 movable portion of the guide bar, as connected with the last mentioned modified form.

Referring to the drawings, numeral 1 55 represents the bearing member, attached in any convenient manner to a table or stand, indicated at 2 in Figure 16, in which bearing member, the main or guide frame 3 is rotatably mounted at 4. The guide frame 3 is composed of two bars between which a slot is provided for receiving a central guide bar 5. The latter is shown in cross-section in Figure 11.

The main frame serves as guide for winding 60 posts indicated at 6 which are adjustable

longitudinally within the guide frame 3 and which may also be adjusted in the direction of their center axis.

They are equipped with adjustable discs 7, the distance between which, may be changed 70 to accommodate various sizes of wires.

Associated with guide frame 3, are universal joints which comprise guide blocks 8, preferably clamped to the frame and held in position, by means of bolts indicated at 9. 75

The sliding members are shown in detail in Figures 12 and 13, where the general outline is shown to comprise a substantially angular form, having an extension 10 provided with an aperture 11. The longer arm 80 of the guide member is provided with guide bosses 12 and 13; the latter guide boss is tapped at 14 for receiving bolt 9.

The hole 11 serves to receive a swivel joint indicated at 15 and shown in Figures 14 85 and 15. This swivel joint comprises a rectangular frame 16 provided with an aperture 17 which is cut obliquely as shown at 18. The sides of the frame are enlarged at 19, for accommodating a set screw or any other 90 clamping means 20.

Held by these set screws, is a sleeve 21 which serves as guide for bars 22, at the end of which are adjustably attached coil clamps 23. These coil clamps comprise two flat 95 members, one of which is stationary, the other movable, and which are held together by any convenient means indicated at 24. At the free and extreme end of these clamping discs, there is provided a small pin indicated at 25, which facilitates the clamping of the coil at a tangent of the innermost loop of the coil. The coil clamps are made adjustable and movable as indicated, for instance, at 26 and shown enlarged in Figure 6, where the clamp proper 23 is provided with a slot, while bar 22, also is slotted, through which slots pass clamping bolts 27, which are readily adjustable.

A modified form of the clamp is shown 110 in Figure 7 where the bar 22' is provided with an extension 28, to which one clamping disc is permanently attached, while the other remains adjustable.

Another modified form of the adjustable 115 clamps is shown in Figure 8, where the bar 22'' is provided with an enlargement 29, forming a socket for the clamp extension 30, which is held in adjusted position by means of a set screw 31.

Referring to Figures 1 and 16, slidably mounted upon guide bar 5, are the carriages 32 and 33. The lower carriage 32 is undercut and engages the swallow tail shaped portion indicated at 32' in Figure 11 of guide bar 5. This carriage is preferably held stationary relative to the bar. The upper carriage 33 is movable relative to the bar. 125

Both of the carriages provide wire receiving 130 means which are composed of an angu-

lar member 34 which may be made adjustable relative to the carriage and adjustable blocks 35 which are shown in detail in Figures 2 and 3 in preferred forms, but which 5 may take any desired shape, depending upon the desire to wind heavier or lighter coils. I construct my blocks preferably in the manner shown in these two figures providing them with one longitudinal slot 36 or a cross 10 slot 37, so that these blocks become hollow and provide for accommodation of a clamping screw, indicated at 38.

However, these blocks may be made solid and only with one central hole, as for instance, shown in Figure 4, or they may be entirely solid and provided with an extending pin shown in Figure 5 at 39, which pin 15 engages a slot 40 provided in the carriage 33. In the latter described modification, a 20 clamping bar 41 is employed which is provided with two bolts 42, by means of which the position of block 35 is assured.

In Figure 4, the construction shows that the block is held by bolt 38', but is additionally secured by a special clamp 43 to prevent any breakage of bolt 38' during the operation of spreading the coil. The construction of guide bar 5 is shown in one preferred form in Figure 9, where this bar is broken 25 and pivoted at 44 and is adjustable in angular relation towards guide frame 3.

Another modified form is shown in Figures 10 and 16, where the guide bar is offset or recessed at its free end as indicated at 45, and in the recessed portion, there is provided a hinged member 46 which is adjustable in angular relation to the solid portion of the bar, by any convenient means, as for instance, indicated at 47. The angular deflection of the guide bar end is of very marked importance for the reason that in spreading a coil, it is very often desired to spread it at an angle, to accommodate the circular shape of the future armature for 50 which the coil is intended.

In order to permit the smooth movement of the upper carriage 33, upon the inclined surface of the hinged end portion of the bar 5, the carriage is undercut as indicated 55 at 47' in Figure 20.

Referring to Figure 9, the adjustment of the hinged end of guide bar 5 and the positioning of the latter is facilitated by a hand operated catch 48, which registers with the notches provided in the cylindrical portion of the hinge. The upper carriage 33 may be operated by hand, for which purpose the side lugs 49 (Figure 20) are provided with pins equipped with a handle indicated 60 in broken lines at 50.

Since, however, the manual operation of the carriage proper is rather difficult and tiresome, I have constructed a more mechanical way of actuating the carriage. I provide a detachable end bearing 51 (Figure

16) which may be readily secured to the end of the guide bar 5 and which is equipped with a spindle 52, which latter is operable by a hand wheel 53. This hand wheel is provided with a handle 54, but may take the 70 shape of a helical gear which may be operated by means of a helical pinion 55, driven by a removable flexible shaft connection 56. This helical pinion 55 has its bearing in the extension of detachable end bearing 51. 75 Slidably mounted with the swallow tail or undercut portion of bar 5 is a nut carriage 57, providing a bearing 58 for spindle 52.

This carriage may be equipped with side handles 59 if so desired. At the lower portion of the nut carriage is provided a hinged connection indicated at 60 by means of which the nut arm 61 is connected with the carriage. At the end of the nut arm there is a half-nut 62 provided which engages the 80 spindle 52. The arm 61 has a side lug 61' against which bears a bell crank lever 63 adapted to disconnect manually nut 62 from spindle 52. Nut arm 61 is held in its engaging position by any convenient means as 85 indicated at 64.

An automatic release is provided in connection with the operating mechanism so that when a certain point in spreading the coil is reached, the nut 62 will be quickly 90 disengaged from spindle 52. This automatic release is of course adjustable relative to the guide bar 5 and may be clamped thereto by means of set screws 65 in Figure 19.

The main mechanism of the release consists of a bell crank lever 69 which is of double fork-like shape. It is spring actuated as indicated at 67 and held in normal position shown in Figure 17. The shorter arm 68 of the bell crank is always in position to intercept the nut 62, while the longer arm 69 permits the nut to freely pass by it.

The moment, however, the shorter arm is touched by the oncoming nut, the longer arm is swung violently against the nut as shown 100 by an arrow in Figure 17 and rapidly disengages the nut from spindle 52. Connecting carriage 33 with nut carriage 57, a rod 69' or a chain 70 or any other convenient connecting member, may be provided, which 105 will allow not only a straight pull upon carriage 33, while guide bar 5 is in its normal position, but also allow an angular pull when the end of the bar is swung at angular relation relative to main frame 3.

Referring to Figures 21 and 22, a guide bar 5' is shown, the end of which is hinged as indicated at 71. A carriage 33' is slidably mounted upon guide bar 5' and is capable of sliding over the hinged portion 72 of 110 the guide bar.

At the end of the hinged portion 72, is a detachable frame 73, adapted to be clamped to bar end 72 by means of bolts 74. In this modified form, it is seen that the carriage 115

33' is provided with a lug 75 adapted to receive the end of a pull chain or another kind of flexible connection indicated at 76, and adapted to be pulled by means of a sheave 77, upon which the flexible member 76 is gradually rolled, in which manner, carriage 33' is pulled toward the end of bar end 72.

The sheave may be operated by means of miter gears indicated at 78, and a handle 79, or may be operated directly as shown in Figure 23, where the miter gears are left out and the sheave 77', shown in section in this figure, is operated directly by handle 79'.

It will be seen in this figure that chain 76 is secured to the sheave at 80, thereby causing the chain to be gradually rolled thereon between the flanges of the sheave.

It is obvious that any kind of flexible member may be employed in the operating mechanism, but preferably a link-chain is used.

In Figure 24, there is illustrated another guide bar 5", which is reduced at its end so as to accommodate two flat side bars 81 and 82, which are hinged to bar 5" at 83. The flat bars are connected at their extreme end by a detachable frame indicated at 84, which provides bearings for a sheave 85.

At the lower portion of the guide bars is provided a raising mechanism of any suitable construction, as for instance, indicated at 86. The carriage 33" is adapted to not only slide upon the guide bar 5", but also upon the flat side bars 81 and 82, which may be elevated relative to the guide bar 5", as shown in Figure 24.

The reduced end 87 of guide bar 5", is provided with bearings for another sheave 88. A chain or other flexible element 89 is connected to the carriage at 90 and is directed over idler sheave 85 and idler sheave 88, below guide bar portion 87.

At the end of this guide bar portion and disposed below idler sheave 88, there is provided a bearing 91, accommodating the reduced end 92 of a threaded spindle 93. The other end of the spindle 93 is lodged in suitable bearings, not shown in the drawings. The chain, 89, having passed over the two sheaves and disposed now below the reduced end 87 of guide bar 5", is attached to a split nut indicated at 94, which is normally held apart by means of expansion springs 95.

Adjustably attached to guide bar 5" are two adjustable stops indicated at 96 and 97.

The one end of the split nut 94 is cone-shaped as indicated at 98 and is adapted to engage a solid collar 99 when the latter is thrust against the nut, thus closing the nut into operative engagement with spindle 93.

The moment collar 99 reaches stop 96, the nut travelling in left hand direction will disengage itself from the collar and is

brought apart, and out of engagement with the spindle, thereby stopping the movement of the chain and thus of carriage 33".

When the nut 94 is brought back, by sliding it manually over the spindle, while in open position, and when the nut finally reaches ring 99, the latter causes the nut 94 to close and to engage the spindle.

This operation is accomplished when collar 99 will for instance, abut with stop 97. It is obvious, therefore, that by adjusting stops 96 and 97, the movement of the nut and therefore that of the carriage may be set to any desired distance.

Spindle 93 may be operated either by handle or by means of a flexible shaft 100 which engages a square end 101 of the spindle by its socket 102.

Operation.

In order to wind a coil, first a wire is placed about winding post 6 and is permitted to pass between the angular extensions 34 and the adjustable blocks 35 of the carriages. The guide frame is now rotated until the proper amount of windings are made.

When a sufficient number of turns have been made, the clamp discs 7 are disengaged to free the now plainly wound coil.

Now, the noses of the coil are clamped into clamps 23. The guide bar is either permitted to remain straight or its end adjusted at the desired angle and, either of the operating mechanisms shown in the drawings, is set in motion by hand or power, thereby causing the movement of the slideable carriages 33 or 33" or 33".

It is obvious that prior to moving the carriage, the stop means are adjusted to the desired point whereby an automatic stop of the carriage is assured. In this manner, any number of coils of the same shape and dimension may be produced in rapid succession.

The moment one of the coils is finished, that is, wound and stretched or shaped, it is very easy to disengage the same from the wire receiving means provided at the carriages. The coil is slipped over the guide bar and removed, and the procedure of winding the next coil is repeated.

While I have shown and described specific forms of my device, and particularly various ideas of the operating mechanisms connected with my device, be it understood that other improvements, changes in design and construction may be readily made within the scope of my invention and I, therefore, reserve for myself the right to make such changes and improvements, without departing from the broad scope of my idea, for which I claim:

1. In an armature coil winding and shaping device, having a guide frame, a guide

bar extending from the latter, a plurality of wire receiving means associated therewith and supported by it, a portion of said guide bar adapted to be adjusted angularly relative to said guide frame, means detachably associated with said guide bar for operating one of the wire receiving means when said guide bar portion is either in its normal position or at an angle relative to said guide frame.

2. In an armature coil winding and shaping device, a guide frame, a guide bar extending therefrom, a portion of said guide bar being adjustable in angular relation toward said guide frame, a pair of adjustable wire receiving means associated with said guide bar, one of said wire receiving means adapted to remain stationary, the other adapted to move in longitudinal direction upon said guide bar, detachable operating means for said movable wire receiving means associated with said guide bar, an adjustable stop mechanism also associated with said guide bar and adapted to check the movement of said movable wire receiving means at a predetermined point.

3. In an armature coil winding and shaping device, as per claim 2, said operating means comprising a spindle, a nut capable of rapid automatic disengagement from the spindle when it reaches a stop device, means for manually disengaging the nut from said

spindle at will, means for transmitting the motion from said operating means to said movable wire receiving means and means for actuating said spindle.

4. In an armature coil winding and shaping device, as per claim 2, said operating means comprising a spindle and an automatically releasable nut, engaging said spindle, said adjustable stop mechanism comprising a slidable frame adapted to be set at a desired point upon said guide bar, a fork-like double-armed lever adapted to be engaged at its shorter arm by said nut, thereby causing the longer arm of said lever to force said nut out of engagement with said spindle.

5. In an armature coil winding and shaping device, a guide bar, a hinged extension associated with the latter, means for changing the angular position of said extension relative to said bar, a movable carriage resting on said bar, an operating mechanism associated with said bar and adapted to actuate said carriage, flexible means connecting said operating mechanism with said carriage, and adjustable stop means for limiting the movement of said carriage.

Signed at New York in the county of New York and State of New York this 1st day of December, A. D. 1923.

GEORGE BENDER.
